CARPENTER'S PLANE

Abraham H. Lavietes, Shelton, Conn.

Application December 28, 1942, Serial No. 470,322

1 Claim. (Cl. 145—11)

This invention relates to carpenters' planes and has for an object to provide an improved adjusting means for the blade of this type of plane, and one which is simple and requires a very small number of parts, will be inexpensive to manufacture, and particularly a construction in which not only longitudinal adjustment of the blade may be effected to adjust the depth of cut, but also lateral or angular adjustment may be easily made so that the cutting edge may be easily located parallel to the bearing surface of the bottom plate of the frame to give a uniform depth of cut.

With the foregoing and other objects in view, I have devised the construction illustrated in the accompanying drawing forming a part of this specification. It is, however, to be understood that the invention is not limited to the specific details and arrangement shown, but may employ various changes and modifications within the scope of the invention.

In this drawing:

Fig. 1 is a top plan view of the device;

Fig. 2 is a vertical longitudinal section;

Fig. 3 is a top plan view of a portion of the adjusting mechanism;

Fig. 4 is a transverse section substantially on line 4—4 of Fig. 3;

Fig. 5 is an elevation of the adjusting screw before assembly, and

Fig. 6 is a side and elevation of the adjusting head for the screw.

The device comprises the body 10 having the usual bottom plate 11 provided with a flat smooth undersurface to ride on the surface of the work, with upright side walls or strengthening ribs 12 at the opposite edges thereof. At the front of the bottom plate is a hand knob 13 mounted in any suitable way, as by the bolt 14, and at the rear and is another hand grip 15 mounted on the base by a bolt 16. The bottom plate is provided with a transverse slot 17 through which may project the cutting edge 18 of the blade 19 supported on the upright transverse rib 20 and the inclined transverse wall or rib 21. At the upper side of the blade, to hold it in position, is the clamp plate or block 22 adapted to press at its lower end 23 on the top of the blade a short distance above the cutting edge, and it has a transverse groove 24 in its top wall in which may seat the transverse rod 25 mounted at its opposite ends in the upright side walls or ribs 12. The top surface of the lower edge 23 may be curved or rounded to form a breaker for the chips. The clamp plate 22 also carries a clamping screw

26 threaded in the plate and adapted to press against the blade 19 at its lower end.

The clamp plate 22 is provided with two upright longitudinally spaced lugs 27 and 28 which may be formed integral with the plate and between them the plate is provided with a longitudinal slot 29 extending therethrough. These lugs 27 and 28 form bearings for the adjusting screw 30, the inner or lower end of the screw being reduced as indicated at 31 for bearing in the lug 27, the reduction forming a shoulder 32 to engage the upper surface of the lug while the upper end portion 33 is left smooth for bearing in the lug 28. The upper end is reduced at 34 to receive a knurled knob or head 35 which forms a finger grip for operating the screw. This can be a disc of suitable thickness with a central opening 36 made slightly smaller than the reduced portion 34 so that it may be mounted on the screw by merely forcing this reduced portion into the opening, but it is a forced fit so that the friction is sufficient to retain the knob on the screw and to operate the screw. The inner end 31 is bored or recessed longitudinally as indicated at 37 and the reduced portion 31 is somewhat longer than the thickness of the lug 27.

Threaded on the screw between the lugs 27 and 28 is an adjusting nut 38 which has a downward extension 39 within the slot 29 of the clamping plate and projecting at its free end into an opening 40 in the blade 19. Above the screw 30 this nut has an extension 41 forming a finger grip by means of which the nut may be adjusted or swung laterally. The screw may be assembled in the clamping plate 22 by inserting it through the lug 28 and threading it into the nut 38. The reduced lower end 31 can then be inserted in the lug 27 and the free end of the recessed portion can be spread outwardly or rolled over, as indicated at 42, to retain it in the lug. It will be seen that this is a very simple assembly operation and one by which the necessary assembling operations may be reduced to a minimum. It also greatly simplifies the construction of the screw, as it may be made from a piece of round rod merely threading the proper length and all the turning required is for the reduced portions 31 and 34 at its opposite ends. The screw can therefore be readily made in an automatic screw machine with simple operations and giving very little scrap or waste material.

In use, when it is desired to shift the blade 19 to adjust the depth of the cut, all that is necessary is to loosen the clamping screw 26 and then adjust the blade 19 longitudinally by turning

screw 30. This shifts the nut 38 longitudinally which, acting through its extension 39 in the opening 40 in the blade, will carry the blade with the movements of the nut. If the cutting edge 18 is not parallel with the surface of the base plate 11 the blade can be easily and quickly adjusted to make this cutting edge parallel with the surface by means of the finger grip 41 on the nut 38. That is, by gripping this finger grip 41 and moving it laterally either to the right or left, the lower extension 39 of the nut will be swung laterally and through its action on the sides of the opening 40 in the blade will adjust the upper end of the blade laterally in either direction and thus adjusting the angular position of the cutting edge, and by this means the cutting edge 18 may be located parallel with the under surface of the base 11. When the blade has been adjusted longitudinally, or laterally or angularly to the desired position, it may be clamped in this position by means of the clamping screw 26. The width of the blade is less than the distance between the side walls 12 to permit this angular or lateral movement of the blade. It will be seen that the slot 29 in the clamping plate 22 is considerably wider than the extension 39 of the nut so as to permit sufficient lateral movement of the extension 39 in effecting the angular adjustment of the blade. The cross rod 25 seating in groove 24 in the top of the clamp plate 22 forms a fulcrum for this plate, and the rod and groove coat to hold the plate against longitudinal movement.

It will be seen from the above that this provides a very simple and effective structure which can be manufactured and assembled with a minimum number of operations and with a minimum loss of material in scrap; also that the blade

may not only be readily adjusted longitudinally to properly locate the blade to give the desired projection of the cutting edge below the bearing surface 11 for the desired depth of cut, but 5 further that it may be readily adjusted angularly to insure that this cutting edge is parallel to the surface of the plate 11 to insure a uniform depth of cut throughout the entire width of the blade. As the blade can be thus adjusted, it is 10 not necessary for the operator to insure that the cutting edge is ground at exactly right angles to the sides of the blade, and it readily insures that there is no danger of one edge of the blade being lower than the other to dig into the surface of the work and make a slight ridge in the surface.

Having thus described the nature of my invention, what I claim is:

In a plane of the character described, a base having a transverse slot, an inclined blade having a cutting edge adapted to project through said slot and its opposite end adapted for lateral movement to adjust the cutting edge into parallelism with the base, a clamp plate above the blade, a longitudinally extending adjusting screw carried by the plate, a longitudinal slot through the plate, an adjusting nut on the screw provided with an extension projecting through the second slot and into an opening in the blade to cause the blade to move with the nut, said 20 latter slot being wider than the extension to permit lateral movement of the extension in the slot, and an extension on the nut opposite the first extension providing a lever for turning the nut laterally on the screw to shift the upper end 25 of the blade laterally to adjust the angular position of its cutting edge in the base.

ABRAHAM H. LAVIETES.
